UNITED STATES PATENT OFFICE.

EDWARD LOUNSBURG BROWN, OF NEW YORK, N. Y., ASSIGNOR OF ONE HALF TO
ALFRED R. RODWAY, OF NEW YORK, N. Y.

EXPENSE-TABULATOR.

1,094,299.

Specification of Letters Patent. Patented Apr. 21, 1914.

Application filed August 13, 1913. Serial No. 784,640.

To all whom it may concern:

Be it known that I, EDWARD L. BROWN, a citizen of the United States, and a resident of the city of New York, borough of Manhattan, in the county and State of New York, have invented a new and Improved Expense-Tabulator, of which the following is a full, clear, and exact description.

This invention relates to an expense tabulator which is intended primarily for use by traveling salesmen, whereby each expense as it is incurred can be easily and conveniently recorded on a strip of paper or other table contained in the device for daily or weekly records, there being a suitable printing mechanism that is adapted to be manipulated for printing on the tape various items of expense and amounts thereof. The device, however, is not necessarily limited to use by salesmen, as it can be obviously adapted for use by others where it is desired to make expense and other lists, thereby doing away with the necessity of having paper and pencil handy and of the inconvenience of writing down the entry.

The general objects of the invention are to provide a device of the character referred to which is of comparatively simple and inexpensive construction, reliable and efficient in use and so designed as to be conveniently carried in the pocket so as to be always ready for use.

More specifically, the invention has for its object to provide a recording device in the form of a casing which has on its exterior a table consisting of suitably arranged words, such as items of expense and numbers representing dollars and cents, and within the casing is a type-carrying element having words and dollar and cent numbers corresponding to the same on the casing, and connected with the type element is a slider which the user adjusts to any desired word or number on the face of the casing so as to bring the corresponding word or number on the tape into printing relation, and then by pressing a presser bar the type is pressed against the tape to imprint thereon the name or number desired to be recorded, the printing operation being accompanied by the movement of the tape one space so as to be in position for receiving the next impression.

Another object of the invention is the provision of record tape which is folded

back and forth in layers so as to take up comparatively little space and to dispense with spools or rolls to hold the same, the tape being arranged in a suitable holder or compartment from which it feeds to the printing mechanism and in passing from the latter the tape may be wound on a spool or folded in its original form and the whole record kept for future reference. A tape folded in this manner is useful in adding, tabulating or other machine-receiving tapes.

With these objects in view, and others as will appear as the description proceeds, the invention comprises various novel features of construction and arrangement of parts which will be more fully described hereinafter and set forth with particularity in the claims appended hereto.

In the accompanying drawings, which illustrate one embodiment of the invention, and wherein similar reference characters are employed to designate corresponding parts throughout the several views, Figure 1 is a plan view of the device; Fig. 2 is a longitudinal section taken parallel with the face; Fig. 3 is a transverse section on the line 3-3 of Fig. 2; Fig. 4 is a view of the type-carrying element; Fig. 5 is a detailed sectional view on the line 5-5 of Fig. 2; Fig. 6 is a sectional view of the slider; and Fig. 7 is a view of a portion of a tape or paper with expense entries shown thereon.

Referring to the drawing, A designates a suitably constructed casing that is preferably of such size as to be conveniently carried in a pocket of one's garment and on the face of the casing is a table B divided into spaces 3 each containing a word 4 or number 5. In the present instance the table is such as would be used by a traveling salesman, and the words shown are of the various items of expense that a salesman accounts for to his employer, and the numbers are in terms of dollars and cents so that the amounts of the various expenses can be recorded.

Within the casing A is a type-carrying element 6 which is shown as an endless strip of rubber that passes around guide pulleys or rollers 7 mounted on spindles 8, as clearly shown in Fig. 5, and on one-half of this strip of rubber 6 are formed in type words 9 and numbers 10 to correspond to the words and numbers in the table B on the face of the casing A. This type-carrying element 6

is adapted to be moved to bring any word or number in printing relation by means of a slider C that extends across the face of the casing A with its ends 11 and 12 slidably connected with one side of the casing A and with a presser bar 13 at the opposite side. This presser bar is formed with a bent lug or arm 14 which passes through a slot 15 in the upper face of the casing A and connects with the type-carrying element 6 so that as the slider is moved back and forth between the ends of the casing the type-carrying element 6 is moved correspondingly. The slider may be mounted in place in any suitable manner, as, for instance, by forming a groove 15 in the side 16 of the casing A for receiving an ear or lug 17 on one end of the slider, such lug having an offset portion 18 which engages in the channel 15, and the end 12 of the slider is formed with a similar lug 19 which has a depressed or off-set portion 20 which engages in a longitudinal groove or channel 21 in the presser bar 13. Arranged in the channels 15 and 21 of the casing and presser bar respectively are longitudinal wires 22 and 23 which form retainers to hold the lugs 17 and 19 slidably engaged with the casing and presser bar. In adjusting the slider the ends 11 and 12 are gripped by the finger and thumb of one hand, as indicated in Fig. 3, while the other hand grips the ends of the casing, and when the device is so held the slider C can be moved back and forth to shift the type-carrying element to bring any desired number or word to printing position.

The slider C forms an index device or indicator in the adjusting of the type-carrying element. For this purpose the left edge of the slider C is straight and it is adapted to coöperate with index lines 24 in the words and number spaces of the table B, such index lines being arranged in a predetermined order or according to the order in which the words and numbers appear on the type-carrying element 6, Fig. 4. More particularly, the index lines 24 are arranged in series of steps, the lines of each series corresponding to seven words or numbers and extending transversely or vertically of the table B, Fig. 1, and the several series are spaced apart longitudinally of the table. Furthermore, the adjacent index lines are spaced apart a distance equal to the distance between adjacent words or numbers on the type element 6. When the slider or indicator C is in the position shown in Fig. 1, that is, with its straight edge registering with the index line in the space of the table B, in which 4.00 appears, the type-carrying element 6 will be so disposed that the 4.00 number of the said element will be in printing position. When the indicator C is in alignment with the index line in the space containing the word "Tips" the type-car-

rying element 6 will be in such position that the word "Tips" thereon will be in printing relation to the paper or tape in the device, so that it is merely necessary for the operator to shift the slider or indicator C to the required index line and then operate the printing mechanism. 70

The pressing of the type element against the strip of paper or tape 25 is accomplished by a platen 26, Fig. 2, which is connected by a shank 27 with the presser bar 13, and on the side of the type element 6 opposite from the platen is the bed 28 over which the tape 25 is directed by the fixed guides 29 and 30, the bed 28 being in fact the central portion of the guide 29, and the guide 30 is made in two parts separated to admit of the bed between them. The presser bar is adapted to be operated by the slide C while the same is grasped between the thumb and finger, as shown in Fig. 3, and for this purpose the slide C is made in two sections *a* and *b*, telescopically connected, the section *b* being the part that engages with the presser bar. Behind the presser bar are springs 31 which hold the bar projected, and this bar is provided with terminal members 32 which slide in openings 33 at the adjacent corners of the casing, said members having lugs 34 disposed inside the casing for holding the presser bar attached to the casing and yet allowing of free movement of the bar. In the operation of printing it is merely necessary to move the slider to the right or left to bring it opposite the desired word or number, and while the slider is still held a pressure is applied to the part *b* of the slider with the result that the platen 26 engages the type-carrying element 6 and presses the same against the tape, whereby an impression is made, the type of the tape being inked by inking rolls 35 mounted adjacent the bed 28. 95

The means for feeding the tape in the present instance is shown as a roll 36 mounted in the casing and having a ratchet wheel 37 with which engages a yielding pawl 38 that is mounted on a slide 39, which slide is pivotally connected with a lever 40 that is fulcrumed at 41 and has a pivotal connection 42 with the shank 27 of the platen 26, so that as the platen and presser bar are moved inwardly the lever 40 will be operated in a direction to drag the pawl 38 over a tooth of the ratchet wheel 37, 115 and when pressure is released from the presser bar the springs of the latter will restore the parts to normal position and thereby cause the pawl 38 to turn the ratchet wheel one step, whereby the tape 25 will be moved along over the bed 28 as the tape winds on the drum 36. The tape 25 is of any suitable length and is folded back and forth in a zigzag fashion and mounted in a compartment or holder 40a in the casing 120 125 130

of the device. By folding the tape in this manner a large piece can be held in a comparatively small space, and a holding spool for the tape is obviated, yet the tape can 5 readily feed from the zigzag pile without tearing, twisting or becoming otherwise deranged. The compartment 40^a that holds the folded tape is formed by the top and bottom of the casing A, the ends and side 10 walls thereof and the guide 29. The folded tape is set loosely into this compartment so as to readily unfold as the tape is fed through the printing mechanism. By folding the tape no special means other than the 15 compartment is necessary to hold the tape.

From the foregoing description taken in connection with the accompanying drawings, the advantages of the construction and method of operation and of the device 20 shown will be readily understood by those skilled in the art to which the invention appertains, and while I have described the principle of operation, together with the device which I now consider to be the best 25 embodiment thereof, I desire to have it understood that the device shown is merely illustrative, and that such changes may be made when desired as are within the scope of the appended claims.

Having thus described my invention I 30 claim as new and desire to secure by Letters Patent:

1. A device of the class described comprising a casing, a table or scale on the 35 casing, a slider movable to different parts of the table, a tape feeding means in the casing, a bed on which the tape bears at all times, a printing mechanism on the casing for impressing the tape, said mechanism including an endless type-carrying element and a platen, a connection between the slider and element for moving the latter, and a presser bar mounted on the casing and operating the platen to press the said element 45 against the tape.

2. A device of the class described comprising a casing, a table thereon including a serial arrangement of words and numbers, a slider movable over the table and into 50 registry with any word or number, a printing mechanism in the casing and including a type-carrying element and a platen, said slider consisting of telescoping sections, a presser bar, a connection between the presser 55 bar and slidable section of the slider, and a tape-holding means against which the type-carrying element is pressed by the platen when the presser bar is actuated.

3. A device of the class described com-

prising a casing, a table thereon including 60 a serial arrangement of words and numbers, a slider movable over the table and into registry with any word or number, a printing mechanism in the casing and including 65 a type-carrying element and a platen, said slider consisting of telescoping sections, a presser bar, a connection between the presser bar and slidable section of the slider, a tape-holding means against which the type-carrying element is pressed by the 70 platen when the presser bar is actuated, a feeding device for the tape, and means actuated by the presser bar for operating the feeding device.

4. A device of the class described comprising a casing, a table thereon with suitable data, a slider on the casing and movable over the said table, a type-carrying element in the casing, a connection between the said element and slider, a presser bar exterior of the casing, a platen, said slider including a movable part having a sliding engagement with the presser bar, the said platen being connected with the presser bar and disposed at one side of the said type-carrying element, a bed in the casing disposed at the other side of the type-carrying element from the platen, means for guiding the tape across the bed, a feeding device for the tape, and a ratchet and pawl means 90 operated by the presser bar for actuating the feeding device.

5. A device of the class described comprising a casing, a table thereon with suitable data, a slider on the casing and movable over the said table, a type-carrying element in the casing, a connection between the said element and slider, a presser bar exterior of the casing, a platen, said slider including a movable part having a sliding engagement 95 with the presser bar, the said platen being connected with the presser bar and disposed at one side of the said type-carrying element, a bed in the casing disposed at the other side of the type-carrying element from the platen, means for guiding the tape across the bed, a feeding device for the tape, said feeding device including a ratchet wheel and 100 a pawl, and a lever connected with the presser bar and with the pawl for actuating the latter.

In testimony whereof I have signed my name to this specification in the presence of two subscribing witnesses.

EDWARD LOUNSBURG BROWN.
